LEWIS C. MYERS, OF FREEPORT, AND GEORGE F. HANDLEY, OF GLENDALE, NEW YORK,
ASSIGNORS TO ROYAL TYPEWRITER COMPANY, INC., OF NEW YORK, N. Y., A CORPO-
RATION OF NEW YORK

TYPEWRITING MACHINE

Application filed December 17, 1931. Serial No. 581,702.

This invention relates to new and useful improvements in typewriting machines generally, although more particularly to a column stop mechanism and a decimal tabular mechanism therefor.

Among the several objects of our invention are to provide a typewriting machine with a series of column stops which are arranged at the rear of the machine, and with a column or tabular stop set key located within the keyboard of the machine; to mount said column stops on a supporting frame for swinging movements in a direction fore and aft of the machine; to automatically and frictionally retain each column stop in either its active or inactive position; to provide a keyboard including a series of decimal tabulating keys which are respectively connected to a corresponding number of stop levers arranged in cooperative relation with the column stops; to provide means whereby one only of the decimal keys may be depressed to actuate one only of the stop levers; to provide a tabular key which is also located in the keyboard and which key may be depressed to operate said particular stop lever without affecting the associated decimal tabulating key or vice versa; and to provide a normally inoperative stop restoring device adapted to be manually moved forwardly into position to be engaged by the column stops during movement of the carriage in either direction to thereby restore all of the column stops to their normal or inactive positions.

In the drawings:-

Figure 1 is a vertical longitudinal section through a typewriting machine embodying our invention, certain parts being omitted for clearance and others being shown in elevation,

The invention is illustrated as applied to the well known Royal machine but many of the features thereof are applicable to other typewriters.

The machine includes the usual main frame 1 which supports a non-shiftable track 2 upon which runs a carriage 3 having end plates 4—4 which support a platen 5. An escapement rack bar 6 is pivotally supported on the carriage and is normally drawn by a spring 7 into engagement with a pinion 8 mounted on the usual shaft. An escapement wheel 9 is mounted to rotate with the pinion 8 and cooperates with the usual escapement dog not shown.

Supported by the end plates 4, 4 of the carriage and disposed in rear of the platen 5 is a column stop frame A which includes upper and lower rack bars 10 and 11 respectively. These bars are held in parallel spaced relation through the medium of end plates 12, 12. Each plate is provided with upper and lower angular recesses 13 and 14 to receive correspondingly shaped extensions on the ends of the rack bars and thereby prevent turning of the bars relative to each other and relative to the plates. Upper and lower clamping screws 15, 16 serve to clamp each plate 12 against the upper and lower bars. Rigidly connected with each end plate 12 is an outwardly projecting threaded stud 17 having a flat upper surface which fits into a correspondingly shaped opening in the adjacent end plate 4 of the carriage. Clamping nuts 18, 18 are mounted on the threaded stud 17 and are clamped against the opposite faces of the end wall 4 of the carriage. The upper and lower stop bars 10 and 11 are rectangular in cross section. The lower face of the upper bar 10 is formed with a series of transversely extending grooves 19 and the upper face of the lower bar 11 is formed with a series of transversely disposed grooves 20, the grooves 19, 20 being arranged in pairs and spaced apart at distances corresponding to letter space intervals. Supported on the stop frame A is a series of column stops B there being one of these stops for each pair of upper and lower grooves 19 and 20. In other words, these stops B are mounted on the stop frame A at letter space intervals. Each stop is of H-shaped construction and includes up-

wardly converging front and rear arms 21 and 22 and downwardly diverging front and rear legs 23 and 24, and a cross bar or connecting portion 25. Each stop B is positioned on the frame A so that the arms 21, 22 are disposed on opposite sides of the upper rack bar 10 and the legs 23, 24 are disposed on opposite sides of the lower rack bar 11, the cross bar or bridge 25 extending between the bars 10 and 11 and into the upper and lower transverse grooves 19 and 20.

The upper ends of the arms 21, 22 are rounded and the distance between these ends is substantially equal to the width of the rack bar 10 so as to permit the stop to swing from an inactive forward position to an active rearward position or vice versa, the rounded ends of the arms constituting pivots or fulcra for the stop. The lower ends of the legs 23, 24 are spaced apart a distance considerably greater than the width of the lower rack bar 11 so as to permit the stop being swung from one extreme position to the other, the legs cooperating with the lower rack bar 11 to limit the swinging movement of the stop. The height of the cross bar or bridge 25 of the stop is less than the distance between the top wall of the groove 19 and the bottom wall of the groove 20. The lower edge of the bridge portion 25 adjacent the rear leg 24 is provided with a flat 26 which rests on the bottom wall of the groove 20 when the stop B is in its inactive or inoperative position, as shown in Figure 6. The lower edge of the bridge portion 25 between the forward leg 23 and the flat 26 is formed with a recess 27 to form a clearance and thereby permit the free rearward swinging of the stop B to the position shown in Figures 5 and 8. It is desirable to frictionally retain each stop B in each of its extreme positions. To this end, each stop B is provided with a spring 28 which is in the form of a spring wire bent between its ends to form upper and lower spring arms 29 and 30 respectively, the bend of the spring engaging a headed stud 31 which is attached to the stop. The arms 29, 30 extend forwardly between the upper and lower rack bars 10 and 11, and the free end of the lower arm 30 is provided with an offset 32 which is located in a seat 33 formed in the front edge of the stop. The free end of the upper arm 29 is curved upwardly and downwardly to form a cam which has sliding engagement with the lower face of the rack bar 10 when the stop B is in its active position as shown in Figure 5, and with the lower front corner of the upper rack bar 10 when the stop B is in its inactive position as shown in Fig. 6.

Thus when the stop B is in its active position as shown in Figure 5, the lower angled edge of the bridge 25 between the front leg 23 and the flat 26 is seated against the rear upper corner of the wall of the transverse groove 20 and is frictionally held thereagainst by 130

the tension of the spring 28 due to the arm 29 thereof bearing against the under face of the upper rack bar 10. When the stop B is moved to its inactive position, as shown in Figure 6, the free end of the upper arm 29 of the spring 28 will snap over the lower front corner of the upper rack bar 10 and the flat 26 will be yieldably retained in contact with the lower wall of the groove 20. It will, therefore, be seen that the stop B is capable of being rocked rearwardly to an active position or forwardly to an inactive position and that yieldable means are employed for automatically and frictionally retaining the stop in either of its extreme positions.

In order to retain the center portions of the upper and lower rack bars 10 and 11 against relative movement, we have provided a tie plate 34 which is formed with upper and lower angular openings 35 and 36 respectively for receiving the upper and lower rack bars 10 and 11. The upper faces of the upper and lower rack bars 10 and 11 are respectively formed with transverse recesses 37, 38 for respectively receiving the upper walls of the openings 35 and 36. The lower end of the plate 34 extends downwardly below the opening 36 and terminates in an arm 39 which underlies the lower rack bar 11. A filler block 40 is disposed between the arm 39 and the lower face of the rack bar 11 and a clamping screw 41 passes through the arm 39 and the block 40 and is threadably engaged in the lower rack bar 11, thereby securely retaining the rack bars 10, 11 and the tie plate 34 against relative movement.

Claims directed to the specific column stops and to the combination of the column stops and rack-bars form the subject matter of our divisional application Serial No. 634,968, filed Sept. 26, 1932.

The column stops B are normally disposed in their forwardly swung or inactive positions, and in order to swing predetermined stops outwardly to active positions prior to stopping the carriage in corresponding column positions, we have provided a tabular stop set key C which when depressed causes a pusher finger to be moved rearwardly into engagement with the registering column stop B and thereby swing the latter rearwardly into active position. This tabular stop set key C is located in the keyboard and at the right thereof, as shown in Figures 1 and 14. The key C includes a lever 42 which extends rearwardly and is fulcrumed upon a cross rod 43 supported on the main frame 1 and the rear end of this lever terminates in an upwardly extending rock arm 44, to the upper end of which is connected the front end of a pull link 45, the rear end of said link being pivotally connected to a depending arm 46 of a bell crank lever 47 which is fulcrumed on a pivot screw 48 mounted in a lug 49 fixed to the side wall of the main frame 1. The

bell crank lever 47 includes a rearwardly extending arm 50 which is slotted as at 51 to receive one end of a lever 52 which is pivoted intermediate its ends as at 53 to the rear wall of the main frame 1. The other end of the lever 52 is pivotally connected as at 54 to the lower end of a thrust link 55, the upper end of said link being pivotally connected as at 56 to a forwardly extending arm 57 of a bell crank lever 58, the other arm of the lever extending upwardly and forming a stop actuating or setting finger 59, the bell crank lever 58 being fulcrumed at its angle as at 60 to a bracket 61 which is rigidly secured to the rear wall of the main frame 1 of the machine. The tabular stop set key C is held in its normal position, as shown in Figure 1, by a coil spring 62. It will, therefore, be observed that when the tabular stop set key is depressed, the pull link 45 will rock the bell crank lever 47 and thereby lower the arm 50 thereof. This downward movement of the arm 50 will swing the lever 52 so as to move the thrust link 55 upwardly thereby rocking the stop actuating finger 59 rearwardly to engage the registering column stop B and swing the latter rearwardly to its active or operating position.

The ordinary column tabulating stop 63 is pivotally supported intermediate its ends as at 64 to the bracket 61 and is operated by a link 65 attached to the lower end thereof and is connected in the usual manner to a tabulator key lever D which is pivotally mounted on the rod 43 and is disposed at the right hand end of the keyboard which as previously stated is in the usual place at the front of the machine. A spring 66 is connected to the tabulator key lever D and tends to normally support the lever in position. A spring 67 which is fast at one end to the bracket 61 normally holds the stop 63 in its forward position. A carriage release lever 68 which is pivotally supported on the main frame has an arm 69 extending forwardly under a ledge 70 on the rack bar 6 so that when the lever 68 is rocked, the rack is lifted out of engagement with the pinion 8 and the carriage 3 is free to move under the influence of the ordinary driving spring. The lever 68 has a downwardly extending arm 71 which bears against the lower portion of the tabulating stop 63 so that when the latter is pulled forwardly, the lever 68 will be rocked and the carriage released from the escapement.

A series of denominational tabulator stops, preferably ten, each being indicated by the reference character E, are provided for cooperation with the column stops B. The denominational tabulator stops E comprise levers 72, 73, 74, 75, 76, 77, 78, 79, 80 and 81. These levers are disposed vertically in rear of the main frame and are pivoted intermediate their ends on a horizontal shaft 82 mounted

in the bracket 61, the upper ends of the levers forming the stops proper.

In order to release the carriage from control of the escapement mechanism when any of the stop levers E are actuated, a bail 83 is mounted by arms 84, 84 on the shaft 82 and these arms are connected by a cross bar 85 in the rear of the levers E. The tabulating stop 63 has an abutment 86 (Figure 3) which is adapted to be engaged by the bail 83. When one of the denominational tabulating levers E is operated, the lower arm thereof engages the cross bar 85 and swings the bail 83 forwardly to engage the abutment 86 of the tabulating stop 59, thereby rocking the latter a sufficient amount to actuate the carriage release mechanism but not sufficient to bring the stop 63 into cooperative relation with any of the tabular stops B.

When it is desired to write in column formations, the appropriate column stops B are selected and swung rearwardly into active or operating positions upon depressions of the tabular stop set key C. In order to arrest the carriage successively at these different column stop stations, connections are made between the denominational tabulator stop lever 72 and the tabulator key lever D whereby upon depression of said lever D the escapement will be released and the stop lever 72 will be moved forwardly into the path of movement of the oncoming column stop B and thereby arrest the carriage at the proper station. To this end, a rock shaft 87 extends transversely under the various key levers and has its ends journaled in bracket arms 88, 88 fixed to the main frame of the machine. Fixed to the right hand end of the rock shaft 87 is a crank arm 89 which normally extends upwardly and forwardly at an inclination and is provided with a rounded upper end 90, the crank arm being disposed directly below the tabulator key lever D for engagement therewith. Fixed to the left hand end of the rock shaft 87 is a forwardly and downwardly extending crank arm 91 to which is rigidly secured a laterally extending crank pin 92 which underlies a forwardly extending arm 93 of a bell crank lever 94 which is loosely journaled on the rock shaft 87, said bell crank lever including a depending arm 95 to which the front end of a push link 96 is pivotally connected, the rear end of said link being pivotally connected to the lower end of the tabulator stop lever 72. Thus when the tabulator key lever D is depressed, it will engage the rounded end 90 of the crank arm 89 and thereby rock the shaft 87. This in turn will rock the crank arm 91 rearwardly and as a result the crank pin 92 will swing the bell crank lever 94 rearwardly, pushing the link 96 rearwardly, and causing the lever 72 to be swung on its axis thereby moving the upper end thereof forwardly into position to be engaged by the oncoming column stop B.

The lever 72 is yieldingly held in its normal position by means of a coil spring 97 which surrounds the front end of the link 96, the rear end of the spring being secured to the link and the front end being secured to an anchor rod 98 extending transversely of the machine and supported by the arms 88.

Located in rear of the keyboard but forming a part thereof is a horizontal series of denominational tabulator keys F, preferably ten, there being one key for each tabulator stop lever E, the keys F respectively comprising levers 99, 100, 101, 102, 103, 104, 105, 106, 107 and 108. Each denominational key lever F is vertically disposed and is provided intermediate its ends with an offset or stop shoulder 109. Journaled on the rock shaft 87 through the medium of a hub 110 is a forwardly extending rock arm 111 which is pivotally connected to the lower end of the denominational key lever 99. The rock arm 111 overlies a crank pin 112 which extends laterally from the horizontal arm 93 of the bell crank lever 94. A coil spring 113 extends around the hub 110 and has its rear end engaged under a cross rod 98 secured to the main frame and disposed in rear of the rock shaft 87, the front end of the spring underlying the crank arm 111. Thus the spring 113 tends to yieldably retain the denominational key levers 99 against depression. At this point, it will be observed that when the tabulator key D is depressed, the bell crank lever 94 will be actuated to move the stop lever 72 to its operative position, and without affecting the denominational key lever 99. It will also be observed at this time that when the denominational key lever 99 is depressed, the crank arm 111 will through its engagement with the crank pin 112 actuate the bell crank lever 94 and thereby the stop lever 72, without imparting any movement to the tabulator key D. Thus the single stop lever 72 is adapted to be moved from its normal position to operative position by either the tabulator key D or by the denominational key lever F, 99, and that the depression of either key will not affect movement of the other.

The remaining denominational keys are connected to the remaining stop levers by identical means and therefore the description of one of said means will suffice. Each of the denominational key levers 100—108, is connected at its lower end to a forwardly extending arm 115 of a bell crank lever 116 which through the medium of a hub 117 is journaled on the rock shaft 87. The downwardly extending arm 118 of each bell crank lever is pivotally connected to the forward end of a link 119, similar to the link 96, the rear end of the link 119 being pivotally connected to the associated stop lever E. It will be understood that each of the links 119 is provided with a spring 97 which functions to normally

hold the denominational key, the associated stop lever, the bell crank 116 and the link 119 in their normal positions. Thus the denominational key levers F may be individually depressed without affecting any of the other key levers of that series.

A comb guide 120, as shown in Figures 1 and 21, is associated with the denominational key levers F in the usual manner, and 10 a stop guide 121 is also associated with said key levers for cooperation with the offset or stop shoulders 109 of said key levers to limit the upward movements thereof.

Our invention also includes a stop restoring device G which is manually movable for cooperation with the tabular stops B for returning the latter to their normal or inactive positions upon movement of the carriage in either direction. This stop restoring device 20 G is mounted on the main frame 1 of the machine at a point in rear of the stops B. Preferably the device G is supported on the upper end of the bracket 61 as shown in the drawings. This device includes a U-shaped frame 122 including a top 123 having depending legs 124, 125 which are pivoted by a stud 126 and a pivot screw 127 to forwardly extending arms 128, 128 of a bracket 129 which is secured to the supporting bracket 61 by screws 130, as shown particularly in Figures 2, 7 and 9. The axes of the pivots 126, 127 are in alignment and in a plane extending parallel with the rack bars 10 and 11 so as to permit the restoring device G to be swung 30 toward and away from the column stops B. The top 123 projects forwardly beyond the supporting legs and the forward edge of said top is formed into a camming surface having a high point 131 located centrally between the attaching legs 124, 125. Two rollers 132, 133 are journaled on vertical axes 134, 135 carried by the top 123. These rollers are disposed on opposite sides of the high point 131 of the camming edge of said top, the camming 40 edge projecting forwardly beyond said roll as clearly shown in Figure 7. In other words, the high point 131 of the camming edge is intermediate the rolls 132, 133, and said rolls project forwardly beyond the camming edge 45 at opposite ends thereof. The rolls 132, 133 function to move easily the column stops B in their first or initial movement over the high points X of the cam surfaces on the cross bars 25 of said stops. The leg 124 projects 50 downwardly below the pivot stud 126 to form a stop arm 136 which is adapted to engage a fixed stop 137 fixed to the arm 128 of the attaching bracket 129 to limit the rearward swinging movement of the device as shown 55 particularly in Figure 5. A coil spring 138 has its upper end engaged with an ear 139 attached to the frame 122 and its other end engaged in an ear 140 secured to the attaching bracket 129. This spring 138 functions 60 to normally retain the restoring device G in

its inoperative position with the arm 136 bearing against the stop 137 as shown in Figure 5. The arm 125 of the frame 122 extends below the pivot screws 127 and terminates in a stop arm 141 which is adapted, 70 when the restoring device G is swung forwardly to operative position, to engage the bracket 129 and thereby limit the forward movement of the device. In order to assist in moving the device to its operative position, 75 we have provided an upwardly extending fingerpiece 142 which is attached to the top 123 of the pivot frame 122. Thus when it is desired to restore the column stops B to their normal or inactive positions, the operator engages the fingerpiece 142 and swings the restoring device G forwardly so as to cause the stops B to first engage one or the other of the rollers 132, 133, depending on the direction of movement of the carriage, and then to 80 engage the high point 131 of the cam edge of the top 123, the parts being so arranged that the high point 131 of the cam will completely restore the column stops B to their normal 85 positions. The keyboard includes the usual letter and numeral keys H which respectively operate type bars I in the usual manner, the keys H being disposed forward of the denominational keys F and at the left of the tabular stop set key C, and the tabulator 90 key D.

From the foregoing, it will be observed that we have provided a typewriting machine with a series of column stops which are arranged at the rear of the machine, and with a tabular 100 stop set key located within the keyboard of the machine; that said column stops are mounted on a supporting frame for swinging movements in a direction fore and aft of the machine; that each column stop is automatically and frictionally retained in either its active or inactive position; that the keyboard includes a series of decimal tabulating 105 keys which are respectively connected to a corresponding number of stop levers which 110 cooperate with the column stops; that one only of the decimal keys may be depressed to actuate one only of the stop levers; that a tabular key also located in the keyboard may be depressed to operate said particular stop 115 lever without affecting the associated decimal tabulating key or vice versa; and that a normally inoperative stop restoring device is adapted to be manually moved forwardly into position to be engaged by the column stops 120 during movement of the carriage in either direction to thereby restore all of the column stops to their normal or inactive positions.

We claim:—

1. In a tabulating mechanism for typewriting machines, the combination with a main frame, of a carriage mounted thereon, a series of column stops mounted on the carriage and spaced apart at letter space intervals, a series of column stop levers mounted 125

on the main frame for cooperation with said column stops, a series of decimal key levers, a tabulator key, and operating connections between the respective decimal key levers and 5 the stop levers and between the tabulator key and one only of the stop levers whereby the decimal key lever associated with the one stop lever and the tabulator key may be independently operated for actuating said one stop 10 lever.

2. In a tabulating mechanism for typewriting machines, the combination with a main frame, of a carriage mounted thereon, a series of column stops mounted on the carriage and spaced apart at letter space intervals, a series of column stop levers mounted on the main frame for cooperation with said column stops, a series of decimal key levers, a tabulator key, separate operating connections between the decimal key levers and the respective stop levers including a separable connection between one decimal key lever and the associated stop lever, and operating connections between the tabulator key and said 25 associated stop lever including a separable connection whereby either said one decimal key lever or the tabulator key may be operated independently of the other.

3. In a tabulating mechanism for typewriting machines, the combination with a main frame, of a carriage mounted thereon, a series of column stops mounted on the carriage and spaced apart at letter space intervals, a series of column stop levers mounted on the main 35 frame for cooperation with said column stops, a series of decimal key levers, a tabulator key, separate operating connections between the decimal key levers and the respective stop levers, one of said operating connections including a push link and a separable connection between the link and the associated decimal key lever, and separable operating connections between the tabulator key and said push link.

45 4. In a tabulating mechanism for typewriting machines, the combination with a main frame, of a carriage mounted thereon, a series of column stops mounted on the carriage and spaced apart at letter space intervals, a series of column stop levers mounted on the main frame for cooperation with said column stops, a series of decimal key levers, a tabulator key, a rock shaft, operating connections between the decimal key levers and 55 the respective stop levers including bell cranks journaled on the rock shaft, one of said operating connections including a separable connection between one decimal key lever only and one only of said bell crank levers, and operating connections between the tabulator key and said one decimal key lever including a separable connection with the rock shaft and a separable connection between the rock shaft and said one bell crank 60 lever.

5. In a tabulating mechanism for typewriting machines, the combination with a main frame, of a carriage mounted thereon, a series of column stops mounted on the carriage and spaced apart at letter space intervals, a series of column stop levers mounted on the main frame for cooperation with said column stops, a series of decimal key levers, a tabulator key, a rock shaft, a crank arm journaled on the rock shaft and having pivotal connection with one only of the decimal key levers, a bell crank lever journaled on the rock shaft and having a crank pin overlying said crank arm, a push link connecting said bell crank lever and one only of said stop levers, operating connections between the other decimal key levers and the other stop levers, a crank arm fixed to the rock shaft and having a crank pin overlying the bell crank lever, and a second crank arm fixed to the rock shaft and located directly under the tabulator key and having a sliding contact therewith.

6. In a tabulating mechanism for typewriting machines, the combination with a main frame, of a carriage mounted on the main frame at the rear thereof, type bars movably mounted on the main frame for cooperation with the platen, key levers associated with the type bars for operating the latter and arranged in a keyboard at the front of the main frame, a series of column stops mounted on the carriage and spaced apart at letter space intervals, a series of column stop levers mounted on the main frame for cooperation with the column stops, a series of decimal key levers forming part of the keyboard, operating connections between the decimal key levers and the respective stop levers, a tabulator key forming part of the keyboard, and operating connections between the tabulator key and one only of said stop levers and including a part of the operating connections between said one stop lever and the associated decimal key lever.

7. In a tabulating mechanism for typewriting machines, the combination with a main frame, of a carriage including a platen mounted on the main frame at the rear thereof, type bars movably mounted on the main frame for cooperation with the platen, key levers associated with the type bars for operating the latter and arranged in a keyboard at the front of the main frame, a series of column stops spaced apart at letter space intervals and independently mounted on the carriage for movement from an inactive forward position to an active rearward position and vice versa, a series of column stop levers mounted centrally on the main frame in rear of the column stops for cooperation with such stops as are moved to active positions, a series of decimal key levers forming part of the keyboard, a tabulator key forming part of the keyboard, operating connections

between the respective decimal key levers and the stop levers and between the tabulator key and the one only of the stop levers whereby the decimal key lever associated with the
5 one stop lever and the tabulator key may be independently operated for actuating said one stop lever, and means for moving predetermined column stops from inactive to active positions including a tabular stop set
10 key lever forming a part of the keyboard.
8. In a tabulating mechanism for typewriting machines, the combination with a main frame, of a carriage mounted thereon, a series of column stops mounted on the carriage
15 and spaced apart at letter space intervals, a series of column stop levers mounted on the main frame for cooperation with said column stops, a series of decimal key levers, a tabulator key, operating connections between the
20 respective decimal key levers and the stop levers and between the tabulator key and one only of the stop levers whereby the decimal key lever associated with the one stop lever and the tabulator key may be independently
25 operated for actuating said one stop lever, and manually operable means for successively restoring the actively positioned column stops to inactive positions upon movement of the carriage.
30 In testimony whereof, we have hereunto
subscribed our names.

LEWIS C. MYERS.
GEORGE F. HANDLEY.
